TOROIDAL COIL WINDING APPARATUS

Anthony Aveni, Los Angeles, Calif., assignor to Hughes Aircraft Company, Culver City, Calif., a corporation of Delaware

Application December 19, 1955, Serial No. 553,879

2 Claims. (Cl. 242—4)

The device of this invention finds general utility in 15 the field of coil winding and particularly in the winding of relatively small toroidal coils.

Heretofore, numerous problems have existed relative to the winding application of wire about a toroidal core, inasmuch as manual winding is very time consuming and inaccurate, and mechanical winding has been impractical due primarily to the relatively small sizes of toroidal coils that have become necessary in contemporary electrical and electronic circuitry. In this regard, it is not uncommon, in miniaturized electrical devices, to employ toroidal coils that are in the nature of one-eighth of an inch in overall diameter, having a central opening of approximately one-sixteenth of an inch. In such instances it has heretofore been practically impossible to pass a wire carrying bobbin through the opening in the toroidal core due to many factors such as, for example, the necessity for supporting and moving a bobbin or shuttle arrangement while still permitting passage thereof through the central core opening. Prior mechanisms have been either too large, too heavy or propelled in such a manner as to prohibit their use in mechanical winding of these small toroidal cores.

It is, accordingly, one important object of the present invention to provide a novel toroidal coil winding apparatus.

It is another important object of this invention to provide a toroidal coil winding apparatus that may be employed in connection with toroidal cores of small dimensions.

It is still another object of this invention to provide a novel toroidal coil winding apparatus wherein means are provided for supporting a bobbin for movement through a central opening in a toroidal core, and pneumatic means are employed to effect such movement.

A still further object of this invention is to provide a toroidal coil winding apparatus having means for simultaneously rotating a toroidal core about its axis, and pneumatically winding suitable wire upon this core, thus to produce relatively small toroidal coils that are accurate and reliable, such apparatus being adaptable for mass production techniques and utilizing a minimum amount of time.

Other and further important objects of this invention will become apparent from the disclosures in the following detail specification, appended claims and accompanying drawing, wherein:

Figure 1 is a side elevational view, partially diagrammatic and partially in section, showing the toroidal coil winding apparatus of the present invention;

Fig. 2 is a plan view and a portion of the apparatus and support means for a toroidal core, as taken substantially as indicated by line 2—2, Fig. 1;

Fig. 3 is an enlarged elevational view of the spherical bobbin employed with the present apparatus; and

Fig. 4 is a perspective view showing the bobbin, together with a means for preventing inadvertent unwinding of wire carried thereby.

2

With reference to the drawing, the toroidal coil winding apparatus of this invention is adapted for use in the establishment of wire about a suitable toroidal core, indicated generally at 10. The core 10 is generally made from any suitable dielectric or permeable material and may be supported by any of a variety of means such as, for example, by means of a plurality of hour glass shaped rollers 11. The rollers 11 are rotatably mounted on a fixed plate 12 by means of shafts 13, the plate 12 being supported on any suitable support structure 14 having a central opening 15 therein. In order that the core 10 may be positioned within the confines of the rollers 11, the plate 12 may be split as at 16 and hinged by means of a suitable hinge 17, there being a tension spring 18 connected across the split 16, normally to retain and bias the rollers 11 into positions against the outer surface of the core 10. Additionally, the rollers 11 may be covered, on the exterior surface thereof, with a frictional material such as rubber or the like in order to provide a slip free support for the core. The particular design of the rollers 11 also enables use thereof with various sizes of toroidal cores. As shown primarily in Fig. 2, one of the rollers 11 may be driven as by a friction wheel 20, mounted on a shaft 21 that is in turn driven by means of a motor 22, for example.

With reference again to Fig. 1, a toroidal passage structure, indicated generally at 23, is supported in connection with a fixed support structure 24. An axis of the passage structure 23 is spaced from and positioned substantially normal to an axis of the core 10. The passage structure 23 includes a tubular member 25 having end portions 26 and 27 that are flared, positioned adjacent lateral sides of the core 10, and in substantial lateral coextensive alignment with an opening 28 in the core 10. The tubular member 25 is further provided with an annular slot 30 in a radially inwardly directed wall thereof.

In order that air under pressure may be delivered uniformly to the interior of the tubular member 25, a plurality of nozzles 31 extend through a radially outer wall of the tubular member 25 from a common air supply conduit 32, having an entrance conduit 33. The nozzles 31 are positioned tangentially with respect to the tubular member 25, in order that flow of compressed air will be in the direction of the arrows 34 and specifically in a counterclockwise direction, as viewed in Fig. 1.

A bobbin, indicated generally at 35, is positioned for movement within the confines of the tubular member 25. The bobbin 35 includes a spherical body member 36 having an annular groove 37 thereabout. A quantity of wire 38 is wound in the groove 37 and extends therefrom. The body 36 is further provided with a pair of recesses 40 on each side thereof and substantially on the axis of the annular groove 37.

As shown primarily in Fig. 4, means are provided to prevent inadvertent unwinding of the wire 38 from the body 36. This means includes a clip member 41 of spring material having a semicircular band 42, ends thereof being turned back as at 43 and spaced from each other in order to provide an opening through which the wire 38 may be dispensed. The band 42 has arms 44 extending from side areas thereof and providing a means for securing the clip 41 to the body 36, this means including pivot pins 45 that are positioned in the recesses 40 in the body 36. The particular arrangement of the clip 41 also enables rotation of the clip about the body 36, the tension of the band 42 on the body 36 being sufficient as to prevent unwarranted unwinding of the wire from the bobbin.

In operation of the present apparatus, one end of the wire 38, being dispensed from the bobbin 35, is connected as by any suitable means such as, for example,

taping, to the core 10, and the bobbin 35 is positioned in one end of the tubular member 25. Thereafter, compressed air is introduced as at 33, through the conduit 32 and the nozzles 31 into the interior of the tubular member 25, thus to propel the bobbin 25 through the tubular member 25 and the opening 28 in the core 10. It is to be noted that the bobbin 35 is in free motion in travel thereof between the ends 26 and 27 of the tubular member 25 and through the opening 28 of the core 10. As the bobbin makes each successive circular passage through the tubular member 25, the wire 38 will be looped in substantially the manner shown by the dotted lines in Fig. 1 and will be drawn from the quantity provided on the body 36 of the bobbin 35 as required for winding about the core 10. Additionally, as described hereinbefore, the core 10 will be rotated on its own axis whereby properly to space the various windings of the wire 38 about the core. When the winding of the core 10 is completed, the air entering as at 33 may be discontinued, thus to stop travel of the bobbin 35 and permit the wire 38 to be trimmed to length.

Inasmuch as the bobbin 35 utilized herein is spherical and relatively simple, it is possible to utilize this structure with relatively small toroidal cores and the winding thereof. Additionally, inasmuch as no mechanical connection is provided between the bobbin motive means and the bobbin, little or no difficulty is experienced in the passage of the bobbin through the opening 28 in the core 10.

Having thus described the invention and the present embodiment thereof, it is desired to emphasize the fact that many modifications may be resorted to in a manner limited only by a just interpretation of the following claims.

What is claimed is:

1. A winding apparatus for toroidal coils disposed about a toroidal core comprising, in combination: a support for said toroidal core, said support including a plurality of rollers engageable with an outer surface of said core; means to drive at least one of said rollers; a toroidal tubular member defining a pneumatic passageway, said tubular member having an axis positioned substantially normal to an axis of said core and spaced therefrom; end portions on said tubular member, said end portions being positioned on lateral sides of said core and closely adjacent thereto; an annular slot in a radially inwardly directed wall of said tubular member; a spherical bobbin

adapted for movable disposition in said tubular member; a quantity of wire wound about said bobbin, said wire being adapted for disposition from said bobbin, through said annular slot and about said core; clip means carried by said bobbin and overlying said quantity of wire for restricting unwinding of said wire from said bobbin; and air jet means for tangentially delivering air under pressure to said tubular member, whereby to propel said bobbin along a circular path through said tubular member and a central opening in said core to wind said wire onto said core, said rotation of said core serving to space winding about said core.

2. A winding apparatus for toroidal coils disposed about a toroidal core comprising, in combination: a support for said toroidal core, said support including a plurality of rollers engageable with an outer surface of said core and rotatably mounted on said support; means to drive at least one of said rollers; means to displace at least one of said rollers to permit initial positioning of said core; a toroidal tubular member defining a pneumatic passageway, said tubular member having an axis positioned substantially normal to an axis of said core and spaced therefrom; flared end portions on said tubular member, said end portions being positioned on lateral sides of said core, closely adjacent thereto and substantially on said axis thereof; an annular slot in a radially inwardly directed wall of said tubular member; a spherical bobbin adapted for movable disposition in said tubular member; a quantity of wire wound about said bobbin, said wire being adapted for disposition from said bobbin, through said annular slot and about said core; clip means carried by said bobbin and overlying said quantity of wire for restricting unwinding of said wire from said bobbin; and multiple air jet means for tangentially delivering air under pressure to said tubular member, whereby to propel said bobbin along a circular path through said tubular member and a central opening in said core to wind said wire onto said core, said rotation of said core serving to space winding about said core.
